(57) **CLAIM**

The ornamental design for a jersey frame, as shown and described.

DESCRIPTION

FIG. 1 is a perspective view of my ornamental design for a jersey frame.

FIG. 2 is a front elevation view of the jersey frame of FIG. 1. FIG. 3 is a rear elevation view of the jersey frame of FIG. 1. FIG. 4 is a left side elevation view of the jersey frame of FIG. 1.

FIG. 5 is a right side elevation view of the jersey frame of FIG. 1.

FIG. 6 is a top plan view of the jersey frame of FIG. 1; and, FIG. 7 is a bottom plan view of the jersey frame of FIG. 1. The broken lines shown in the drawings are directed to portions shown for environmental purposes that form no part of the claimed design.
